UNITED STATES PATENT OFFICE.

THOMAS WESTGARD, OF GREAT FALLS, MONTANA.

MULTISTAGE AIR COMPRESSOR OR WATER PUMP.

Application filed May 5, 1928. Serial No. 275,394.

This invention relates to multi-stage air compressors or water pumps.

An important object of the invention is to provide in a device of this character a construction which may be readily manufactured and which will provide a compact and efficient mechanism for pumping fluids.

A further object of the invention is to provide in a device of this character a construction such that when the apparatus is used as a water pump, the water may be raised to a greater level than is ordinarily possible with such apparatus.

A further and more specific object of the invention is to provide in a construction of this character a multi-stage impeller organization in which the impellers of the different stages are arranged in series and are co-axial and the driving mechanism therefor is disposed at one end of the completed structure.

These and other objects I attain by the construction shown in the accompanying drawings, wherein for the purpose of illustration is shown a preferred embodiment of my invention and wherein:

Figure 1 is a plan view of a pump constructed in accordance with my invention.

Figure 2 is a section on the line 2—2 of Figure 1;

Figure 3 is a section on the line 3—3 of Figure 1;

Figure 4 is a section on the line 4—4 of Figure 3.

Referring now more particularly to the drawings, the numeral 10 generally designates a base having arranged thereon a horizontally disposed cylindrical casing, generally designated at 11, and formed in two sections 12 and 13 bolted together. At one end, this casing communicates with an intake neck 14 which is disposed at right angles thereto and is connected thereto by an elbow 15. Within the neck 14, means, indicated at 16, are provided for supporting a plurality of screens 17, the purpose of which will hereinafter appear.

The opposite end of the casing 11 communicates with a reduced outlet 18 having a check valve 19 disposed therein. The exterior wall of the elbow 15 is provided with a packing gland 20 and forms a support for one end of a gear casing 21, the adjacent end wall 22 of which is spaced from the packing gland to permit ready access thereto. Extending into the opposite end wall 23 of the gear casing is an input shaft 24, at present

shown as directly connected to the armature shaft 25 of a motor 26 which is mounted upon the base.

Within the casing, this shaft is mounted in bearings 27 supported from the walls of the casing and has secured thereto a series of gears 28, 29 and 30 of different sizes. The gear casing is provided with a second set of bearings 31, 32 and 33 receiving respectively 60 a solid shaft 34 and hollow shafts 35 and 36. These shafts have secured thereto gears 37, 65 38 and 39 meshing with the gears 28, 29 and 30. It will be noted that these shafts will be driven at different speeds, the shaft 34 rotating 70 at the highest speed. The shafts 34, 35 and 36 extend through the packing gland 20 into the casing 11 and are disposed axially with relation thereto.

Within the casing 11 are arranged longitudinally spaced bearings 40, 41 and 42 receiving respectively the shafts 36, 35 and 34, the bearing 40 being disposed most nearly adjacent the stuffing box 20. These bearings are preferably supported from the lower wall 80 of the casing by vertical standards 43 and are braced to the side walls thereof by horizontally extending arms 44. The caps 45 of these bearings are accessible and removable when the cover section 12 of the casing is removed. Between the bearings 40 and 41, the interior diameter of the casing is reduced, as at 46, and between the bearings 41 and 42 is again reduced, as at 47.

Secured to the shaft 36 in advance of the bearing 40 is a series of impellers 48 while the shaft 35 between the bearings 40 and 41 and the shaft 34 between the bearings 41 and 42 are provided with impeller series 49 and 50. The impellers of these series preferably 90 comprise fan-like blades 51, the peripheries of which are connected by an annular rim 52, which operates in close proximity to the wall of the casing. The space provided in reducing the diameters of the casing, as at 46 and 100 47, is preferably employed in the formation of water jackets 53.

Each of the shafts 35 and 36 within the casing and at its bearing 41 is packed to the shaft contained therein, preferably by 105 sealing rings 54 carried by the tubular shafts 36 and 35.

It will be obvious that in operation, the impeller blades 48, 49 and 50 successively operating on the fluid will cause the same to move 110 at an accelerated pace through the casing 11 resulting in a greatly increased pressure at

the discharge. Where water is being pumped to a higher level, air is added to the water entering the neck 14 and since this water is broken up by the screens 17, will be thoroughly intermingled therewith, so that the water may be lifted to much greater heights than would otherwise be possible. These screens further serve to remove from the water any foreign substance which may be contained 10 therein and which will act injuriously upon the bearings and impellers of the compressor or pump.

With a construction such as that hereinbefore set forth, the various parts are made 15 readily accessible for inspection or repair and a conservation of space results, thereby enabling efficient use of the device as an air compressor or water pump in mines or other places where space is of necessity limited.

20 A structure of this character may be conveniently employed as an air compressor, supplying compressed air for use by rock drilling, riveting, or mining machines or for other purposes.

25 Since the construction hereinbefore set forth is capable of a certain range of change and modification without materially departing from the spirit of the invention, I do not limit myself to such specific structure except 30 as hereinafter claimed.

I claim:

1. In a multi-stage rotary air compressor and water pump, a cylindrical casing reducing in diameter from its intake toward its exhaust end, a plurality of longitudinally spaced bearings in the casing, a plurality of concentric shafts projecting into one end of the casing and having their ends supported by said bearings, impeller blades carried 40 by said shafts, and means for rotating said shafts at different speeds.

2. In a multi-stage rotary air compressor and water pump, a cylindrical casing reducing in diameter from its intake toward its exhaust end, a plurality of longitudinally spaced bearings in the casing, a plurality of concentric shafts projecting into one end of 45

the casing and having their ends supported by said bearings, impeller blades carried by said shafts, a neck communicating with the 50 intake end of the casing through an elbow, a gland in the exterior wall of said elbow through which said shafts extend and a gear casing in which the opposite ends of the shafts have bearing, a gear upon the last 55 named end of each shaft and a drive shaft having gears engaging the gears of said concentric shafts.

3. In a multi-stage rotary air compressor and water pump, a cylindrical casing reducing in diameter from its intake toward its exhaust end, a plurality of longitudinally spaced bearings in the casing, a plurality of concentric shafts projecting into one end of the casing and having their ends supported 60 by said bearings, impeller blades carried by said shafts, and common driving means for said shafts rotating the shafts at different speeds and the shafts whose impellers coact with the reduced portions of the casing at 70 a higher rate of speed than the remaining shaft.

4. In a multi-stage rotary air compressor and water pump, a cylindrical casing reducing in diameter from its intake toward its exhaust end, a plurality of longitudinally spaced bearings in the casing, a plurality of concentric shafts projecting into one end of the casing and having their ends supported by said bearings, impeller blades carried by 80 said shafts, a neck communicating with the intake end of the casing through an elbow, a gland in the exterior wall of said elbow through which said shafts extend, a gear casing in which the opposite ends of the shafts 85 have bearing, a gear upon the last named end of each shaft, and a drive shaft having gears engaging the gears of said concentric shafts. the first named ends of the outer shafts being 90 each sealed to the shaft next adjacent thereto.

In testimony whereof I hereunto affix my signature.

THOMAS WESTGARD.
